ROTARY MACHINE.

1,175,153.

Specification of Letters Patent.

Patented Mar. 14, 1916.

Application filed March 25, 1913. Serial No. 756,833.

To all whom it may concern:

Be it known that I, RUDOLF KLINGER, a subject of the Emperor of Austria-Hungary, residing at Gumpoldskirchen, near Vienna, Austria-Hungary, have invented certain new and useful Improvements in Rotary Machines; and I do hereby declare the following to be a full, clear, and exact description of the invention, such as will enable others skilled in the art to which it appertains to make and use the same.

The present invention relates to rotary machines in which vanes or slides, guided in longitudinal slots of a rotary drum, are caused to slide to and fro in an axial direction by guide surfaces operating upon their ends, and it relates more particularly to that construction of machines of this kind which is described in the U. S. Patent to Pittler No. 894391 dated July 28, 1908, having working chambers formed by radial annular grooves in the rotary drum in which grooves engage stationary abutments fitted to the casing, the vanes or slides being provided with notches by which they are enabled to clear the abutments. In known machines of this kind the vanes are guided by cam surfaces. It follows therefore that the end faces of the vanes and the guiding surfaces touch each other on lines only, thus producing unfavorable conditions of surface pressure and wear.

According to the present invention the controlling device comprises inclined plane surfaces which abut against sliding blocks or shoes having plane sliding surfaces and connected with the ends of the vanes by means of universal joints, so that the said sliding shoes, whatever position they may occupy during the revolution of the drum, are able to adjust themselves accurately to the inclined surfaces. By this means, uniform distribution of pressures over the whole face of the sliding blocks is attained and consequently excessive pressures per surface unit are obviated.

In the drawing Figure 1 represents a constructional form of the invention in horizontal longitudinal section. Fig. 2 is a cross section along line 2—2 of Fig. 1, the outer casing being omitted. Figs. 3 and 4 show modifications of details.

The machine shown in Figs. 1 and 2 comprises a drum *a* mounted on a shaft *b* and provided with longitudinal slots *c* and an-

nular grooves *d*. Abutments *n*, mounted in known manner on the casing *l*, engage with the annular grooves *d*. In the longitudinal slots *c* vanes *e* are guided, provided with notches *f*, which allow them to clear the abutments extending into the annular grooves *d*. The vanes *e*, at their ends are provided with pins *g*, upon which are mounted balls *h*. The latter are lodged in hemispherical recesses of the sliding shoes *i*. At the inner faces of the covers *k* of the casing inclined planes *m* are formed. The covers are mounted in such a position on the casing *l* that their inclined planes *m* are parallel to each other. On these latter the sliding shoes *i* glide with their likewise plane sliding surfaces. The sliding shoes *i* may be pressed over the balls *h*. For this purpose they are preferably not made of metal, but are produced with the aid of high pressure and heat from a composition of resinous and fibrous materials which does not swell up in water.

In Fig. 3 the sliding shoes have the shape of ring segments instead of being circular as illustrated in Fig. 2; they may however have any other suitable shape.

The guide surfaces of the two covers may if desired, be rendered exchangeable, as shown in Fig. 4, so that they can be produced from a metal which is suitable to work together with the material of the sliding shoes. An alloy of iron and nickel has proved to give particularly satisfactory results, inasmuch as exceptionally favorable frictional conditions are obtained between the said alloy and the material of the sliding shoes, while furthermore it offers the advantage of not rusting on the admission of water.

I claim:

1. In a rotary machine the combination of a casing, a rotary drum therein having a circumferential groove and a radial longitudinal slot, an abutment fitted to said casing and engaging into said circumferential groove, a slide axially movable in said longitudinal slot and having a notch corresponding to said circumferential groove, parallel inclined plane surfaces in said casing opposite the ends of said rotary drum, and sliding shoes directly articulated to the ends of the slide by means of ball joints and having plane sliding surfaces in contact with said inclined surfaces.

2. In a rotary machine the combination of a casing, a rotary drum therein having a circumferential groove and a radial longitudinal slot, an abutment fitted to said casing and engaging into said circumferential groove, a slide axially movable in said longitudinal slot and having a notch corresponding to said circumferential groove, parallel inclined plane surfaces in said casing opposite the ends of said rotary drum, sliding shoes in contact with said inclined surfaces, ball sockets therein, balls lodged in said sockets having recesses, and pins on the ends of said slide engaging in said recesses. 45
- 15 3. In a rotary machine the combination of a casing, a rotary drum therein having a circumferential groove and a radial longitudinal slot, an abutment fitted to said casing and engaging into said circumferential groove, a slide axially movable in said longitudinal slot and having a notch corresponding to said circumferential groove, parallel inclined plane surfaces in said casing opposite the ends of said rotary drum, sliding shoes in contact with said inclined surfaces, ball sockets in said sliding shoes, and balls arranged at the ends of said slide and lodged in said ball sockets, said sliding shoes consisting of a material adapted to be pressed over said balls. 50
- 20 4. In a rotary machine the combination of a casing, a rotary drum therein having a circumferential groove and a radial longitudinal slot, an abutment fitted to said casing and engaging into said circumferential groove, a slide axially movable in said longitudinal slot and having a notch corresponding to said circumferential groove, parallel inclined plane surfaces in said casing opposite the ends of said rotary drum, sliding shoes in contact with said inclined surfaces, ball sockets in said sliding shoes, and balls arranged at the ends of said slide and lodged in said ball sockets, said sliding shoes consisting of a material adapted to be pressed over said balls. 55
- 25 5. In a rotary machine, the combination of a casing, a rotary drum therein having a circumferential groove and a plurality of radial longitudinal slots, an abutment fitted to said casing and engaging into said circumferential groove, slides axially movable in said longitudinal slots, each of which slides has a notch corresponding to said circumferential groove, parallel inclined plane surfaces in said casing opposite the ends of said drum, and sliding shoes directly articulated to the ends of the slides by means of ball joints and having plane surfaces sliding in contact with said inclined surfaces. 60
- 30 6. In a rotary machine the combination of a casing, a rotary drum therein having a plurality of circumferential grooves and a plurality of radial longitudinal slots, a plurality of abutments fitted to the casing and engaging into said circumferential grooves, slides axially movable in said longitudinal slots and having notches corresponding to said circumferential grooves, parallel inclined plane surfaces in said casing opposite the ends of said drum, and sliding shoes directly articulated to the ends of the slides by means of ball joints and having plane surfaces sliding in contact with said inclined surfaces. 65
- 35 7. In a rotary machine the combination of a casing, a rotary drum therein having a circumferential groove and a radial longitudinal slot, an abutment fitted to said casing and engaging into said circumferential groove, a slide axially movable in said longitudinal slot and having a notch corresponding to said circumferential groove, parallel inclined plane surfaces in said casing opposite the ends of said rotary drum, sliding shoes in contact with said inclined surfaces, ball sockets in said sliding shoes, and balls arranged at the ends of said slide and lodged in said ball sockets, said sliding shoes consisting of a material adapted to be pressed over said balls. 70
- 40 8. In a rotary machine the combination of a casing, a rotary drum therein having a circumferential groove and a radial longitudinal slot, an abutment fitted to said casing and engaging into said circumferential groove, a slide axially movable in said longitudinal slot and having a notch corresponding to said circumferential groove, parallel inclined plane surfaces in said casing opposite the ends of said rotary drum, sliding shoes in contact with said inclined surfaces, ball sockets in said sliding shoes, and balls arranged at the ends of said slide and lodged in said ball sockets, said sliding shoes consisting of a material adapted to be pressed over said balls. 75
